UNITED STATES PATENT OFFICE.

HENRY L. WALLACE, OF WALLINGFORD, CONNECTICUT.

DESIGN FOR A HANDLE FOR SPOONS, FORKS, OR SIMILAR ARTICLES.

SPECIFICATION forming part of Design No. 34,812, dated July 23, 1901.

Application filed June 25, 1901. Serial No. 66,013. Term of patent 7 years.

To all whom it may concern:

Be it known that I, HENRY L. WALLACE, a citizen of the United States, and a resident of Wallingford, in the county of New Haven and State of Connecticut, have invented a certain new and original Design for the Handle of a Spoon, Fork, or Similar Article, of which the following is a specification.

The drawing illustrates a front view of my novel design of handle shown in connection with the bowl of a spoon, the blade and tine of a fork being indicated in dotted lines.

The leading or material features of my design consist in the convex central panel having a large and small bead on either side and the scroll ornamentations at the two ends of the panel.

In the drawing, A indicates the handle, and B the bowl. The handle comprises a broad blade portion a, a contracted shank b, and a wider part c, adjacent to the bowl.

d represents a convex central panel, e a small rib on either side of the same, and f a larger rib on the outside of the small rib and forming a rounded edge for the sides of the handle. The upper end of this outer rib ter-

minates in a large scroll g, while the lower end is provided with a small scroll h. The inner rib is also provided with a small scroll i at either end. A fleur-de-lis j is located between these lower scrolls, and a pair of attractive foliated scrolls k are arranged on either side of the fleur-de-lis with a central pistil l therebetween. The top ornamentation of the handle also contains an attractive fleur-de-lis m with a double scroll n on either side, the whole arranged to form an attractive pyramidal end.

Having thus described my invention, what I claim, and desire to secure by Letters Patent, is—

The design for the handle of a spoon, fork or similar article, substantially as herein shown and described.

Signed at Wallingford, in the county of New Haven and State of Connecticut, this 21st day of June, A. D. 1901.

HENRY L. WALLACE.
